UNITED STATES PATENT OFFICE.

JOHN C. BUTTERFIELD, OF BELMOND, IOWA.

TRAFFIC SIGNAL.

Application filed July 25, 1921. Serial No. 487,506.

This invention relates to signals of the character employed at street intersections for automatically controlling the flow of traffic past the intersection, the signal working at predetermined intervals to alternately direct the traffic on intersecting streets across the intersection.

The signal is preferably positioned in the center of the intersecting streets, but can be placed on one or more of the corners of the intersection, if desired.

An object of the invention is to construct a signal that can be used to good advantage in the middle of the intersection.

Another object is to eliminate mechanical faults of construction so as to obviate breaking down of the signal when being used.

Another object is to make provision for relative movement between the semaphore and its standard so that if the semaphore be struck by a vehicle it will rotate and not be broken or bent.

Another object is to make provision for swinging the semaphore into vertical position when it is not desired to have the signal in operation.

Another object is to provide timing mechanism reliable in operation so as to effectively and simultaneously control a series of the signaling mechanisms placed at different street intersections.

Other objects and advantages will appear in the subjoined detailed description.

The accompanying drawings illustrate the invention:

Figure 1 is a side elevation of a traffic signal constructed in accordance with the provisions of this invention, the semaphore being shown in solid lines in position for directing the traffic in a direction parallel with the plane of the drawing, broken lines indicating the semaphore in position when it is out of use.

Figure 2 is an enlarged side elevation of the upper portion of the signal shown in Figure 1, a portion of the end of the semaphore being broken away to disclose a spring latch that would otherwise be partly hidden from view.

Figure 3 is an elevation, similar to Figure 2, the parts being mainly in vertical midsection.

Figure 3^a is an elevation of the lower end of the sleeve from the right of Figure 2.

Figure 4 is an enlarged plan view of Figure 1.

Figure 5 is an enlarged broken elevation on the line indicated by x^6-x^5 , Figure 1.

Figure 6 is an enlarged plan section on the line indicated by x^6-x^6 , Figure 1, omitting the bell and transformer.

Figure 7 is an enlarged plan view of the timing mechanism.

Figure 8 is a front elevation of Figure 7, omitting the motor, dotted lines indicating one of the electric contacts in open position.

Figure 9 is an end elevation from the left of Figure 8, dotted lines indicating two of the contacts in the position they occupy corresponding with the dotted position of one of them in Figure 8.

Figure 10 is an enlarged detail of the switch arm-operating ratchet device.

Figure 11 is a diagram indicating the electrical connections for a traffic signal system, two signaling mechanisms and one timing mechanism being indicated.

Figure 12 is a fragmental vertical section of a street showing the wires, connecting the signaling and timing mechanism, embedded in the material of which the street surface is constructed.

The signaling mechanism will first be described: There is provided a suitable housing 1 fastened by screws 2 to a base or pedestal 3 made of cast iron or other suitable material so as to securely hold the housing 1 in position in the center of intersecting streets or on one of the corners of the intersection or wherever else it may be desired to position the signaling mechanism. If desired, the base 3 may be embedded in the street or sidewalk, but this is not necessary. The base 3 weighs several hundred pounds, so that the housing cannot be moved without the exertion of a considerable force. The opposite sides of the housing 1 are provided with doors 4 having perforated ears 5 at their lower ends adapted, when the doors are closed, to register with perforated ears 6 mounted on the base 3 so that padlocks may be used to secure the ears 5, 6 to each other to prevent opening of the doors 4 by unauthorized persons.

The bottom of the housing 1 is indicated at 7 and mounted thereon is a motor 8 having a shaft 9. The shaft 9 is provided near one end with a collar 10 and said shaft is also provided with a friction clutch, one

member 11 of the clutch being fastened by a screw 12 to the shaft 9 and the other member 13 of the clutch being loose on said shaft. Between the clutch member 13 and 5 collar 10 is interposed a coil spring 14 adapted to press the clutch member 13 into frictional engagement with the clutch member 11.

The clutch member 13 constitutes a drum 10 and fastened thereto by a screw 15 is one end of a chain or other flexible line 16. The opposite end of the chain 16 is secured by a screw 17 to the bottom 7. The chain 16 is also secured between its ends, as indicated 15 at 18, to an arm 19 of an oscillatory member, indicated in general by the character 20. The arm 19 is normally held in a direction away from the clutch 12, 13, by a coil spring 21 secured at one end to the arm 20 19 and at its opposite end by a bracket 22 to one of the side walls of the housing 1. When the motor 8 operates it turns the shaft 9 in a direction to wind the chain 16 on the drum 13 so as to turn the member 25 20 in the direction of the arrow *a* in Figure 6. When the slack in the chain 16, between the arm 19 and the screw 17, has been taken up by the turning movement of the drum 13 as just described, if the motor continues to 30 turn, the clutch member 13 will slip so that the motor and other associated operating members already described will not be injured.

The member 20 is loosely mounted on a 35 vertical shaft 23 which, in the instance shown, is of tubular construction. Inserted in the lower end of the shaft 23 is a stud 24 projecting upwardly from the housing bottom 7. The stud 24 and a nut 24' on 40 said stud serve as a step bearing for the shaft 23.

The shaft 23 is provided with a four teeth ratchet wheel 25 engaged by a pawl 26, the 45 pawl and ratchet construction being such that when the motor operates to turn the member 20 in the direction of the arrow *a* the pawl 26 engages the ratchet wheel and turns said wheel, which thus rotates the shaft 23. When the current is cut off from 50 the motor 8, the spring 21 functions to retract or turn the member 20 in a direction opposite to that indicated by the arrow *a*, whereupon the pawl 26 will slip over the teeth of the ratchet wheel 25 so as not to 55 turn the shaft 23 in a reverse direction.

The ratchet wheel 25 is yieldingly held 60 against turning by a flat spring 27, the ratchet wheel having four sides at right angles to one another so that the spring 27 will successively engage the sides of said ratchet wheel to hold it in as many different positions ninety degrees of circle measure apart. It will be clear from this that the ratchet wheel 25 is given a quarter turn 65 each time the motor operates. The spring

27 is mounted on the housing bottom 7. When the ratchet wheel 25 has been turned to a position a trifle more than forty-five degrees from the position shown in Figure 6, the spring 27 aids in turning said ratchet 70 wheel.

The pawl and ratchet device described above will produce the desired intermittent quarter turning of the shaft 23, but it is desirable that the shaft 23 be held against 75 turning independent of the oscillatory member in the direction indicated by the arrow *a*, for a reason that will be made clear hereinafter. To prevent such independent turning, I provide a second pawl 28 operating oppositely to the pawl 26 and both pawls 26, 28 are normally held in engagement with the ratchet wheel 25 by a coil spring 29 fastened at its opposite end to the pawls, which are respectively pivoted 85 at 30 to the member 20.

I provide suitable means to retract the pawl 28 from engagement with the ratchet wheel 25 when the member 20 is turned by operation of the motor 8. Such means, in 90 the instance shown in the drawings, embody a coil spring 31 fastened at one end to the pawl 28 and at its opposite end to the adjacent side of the housing 1. When the member 20 is in the retracted position shown 95 in Figure 6 of the drawings the spring 31 will be under no tension. When, however, the member 20 is turned in the direction of the arrow *a*, the spring 31 will be lengthened sufficiently to put it under tension, and such tension operates to retract the pawl 28. It is necessary to retract the pawl 28 in this manner, so that on the return movement of the member 20, due to the pull of the spring 21, the pawl 28 will not engage 100 the ratchet wheel 25 and thus turn the shaft 23 in a reverse direction to that effected by the pawl 26.

Mounted on the upper end of the shaft 23 is a semaphore 32 and, though said semaphore may be fixed to said shaft, it is preferable to make provision for turning of the semaphore about the axis of the shaft 23 when said shaft 23 is held stationary, as explained above, so that a vehicle accidentally 110 striking the semaphore will simply cause the semaphore to turn on the shaft 23 and thus not break or injure the signalling mechanism. The construction which I employ 115 at present for thus mounting the semaphore is as follows: The semaphore 32 is hollow and is provided with a vertical sleeve 33 fitting around the upper end of the shaft 23. The lower end of the sleeve 33 is of irregular contour to form a cam 34 which rests upon a roller 35 mounted on a screw 36 projecting from the shaft 23. If the semaphore 32 be turned relative to the shaft 23 to the right or left in Figure 2, the cam 34 125 will ride up on the roller 35 against the 130

force of gravity, and gravity will, therefore, tend to return the semaphore to normal position when it is released. This tendency to return to normal may be emphasized by a suitable coil spring 37 fastened at its upper end by a stud 38 to the semaphore 32 and at its lower end by a stud 39 to the shaft 23. This spring 37 pulls downwardly on the semaphore 32 so as to tend 10 to move the cam 34 into the position shown in Figure 2.

When it is not desired to have the signal operate, it is preferable to swing the semaphore into vertical position so that it 15 will be non-indicative of traffic flow past the intersection, and also so that there will be less danger of a passing vehicle striking the ends of the semaphore. For this reason, the semaphore 32 is pivoted to the sleeve 20 33, the pivot in this instance being formed by the stud 38. It is now clear that the semaphore 32 may be swung into the vertical position indicated in broken lines in Figure 1. When thus swung into vertical position, the semaphore 32 may be yieldingly 25 held by a resilient hook or latch 40 fastened near one end of the semaphore and adapted to be sprung sufficiently by the shaft 23, when the semaphore is swung into the vertical 30 position indicated in broken lines *c*, Figure 1, to grip the shaft between the hook and the inside face of the semaphore.

If the semaphore 32 be thus pivoted to the sleeve 33, spaced ears 41 will be provided 35 on one face of the semaphore to engage on opposite sides of the spring 37 when the semaphore is in the horizontal position. The notch formed by the ears 41 is positioned substantially in vertical alignment with the 40 stud 38. When the semaphore 32 is forcibly turned in its vertical path of motion to the signaling and non-signaling positions, the spring 37 will readily snap in and out of the notch between the ears 41. Positioned 45 on the inner face of one side of the housing is an electric bell 42 and also a suitable bell ringing transformer 43.

The timing mechanism will now be described: There is provided a suitable base 50 44 which may form the bottom of a case or housing that is not shown in full and that may be employed for housing the timing mechanism, or, if desired, the timing mechanism 55 may be mounted in the housing 1 of the signaling mechanism. Mounted on the base 44 is an electric motor 45 having a horizontal shaft 46 which is coupled at 47 to a worm shaft 48 provided with a worm 49. The worm 49 is in mesh with a worm gear 50 mounted on a transverse horizontal shaft 51 which is also provided with a spur pinion 52 in mesh with a spur gear 53. The shaft 48 is journaled in a bearing 54 and is provided with a collar 55 to take up end thrust. 60 The shaft 51 is journaled in bearings 56.

The spur gear 53 is mounted on a shaft 57 journaled in bearings 58, 59.

The shaft 57 is provided near one end with an eccentric 60 which produces reciprocatory movement of a detent 61 engaging 70 a toothed wheel 62 mounted on one end of a shaft 63. Operation of the eccentric 60 effects step by step rotation of the wheel 62, which is thus turned comparatively slowly. Also engaging the toothed wheel 62 is a 75 check pawl 64 which is pivotally mounted at 65. Both detent 61 and pawl 64 are yieldingly held in engagement with the toothed wheel 62 by a coil spring 66 fastened at its opposite ends to said detent and pawl. 80

The opposite end of the shaft 63 is provided with a switch arm contact 67 adapted once in each revolution of the shaft 63, to engage an electric switch contact 68 which is pivotally mounted at 69 on a bracket 70 suitably insulated at 71. The contact 68 is normally held in the path of travel of the contact 67 by a coil spring 72 fastened at one end to the upper end of the contact 68 and at its opposite end to the bracket 70. The path of movement of the contact 67 is substantially at right angles to the path of movement of the contact 68.

The contact arm 67 has another function than closing an electric circuit and, therefore, 95 it is adapted once in each revolution to engage one of four arms 73 fast on the shaft 74 which is journaled in bearings 75, 76. These arms 73 are at right angles to one another and project from a four-sided hub 77 which constitutes a cam. In contact with the cam 77 is a spring arm 78 fastened at its lower end to the base 44 and carrying an electric contact 79 at its upper end. As the cam 77 turns it moves the contact 79 into engagement with a stationary electric contact 80 mounted on the upper end of a standard 81 which is fastened to the base 44. Because of its square cross section, the cam 77 causes engagement of the contacts 79, 80 four times to each revolution of the shaft 74, or, in other words, the electric circuit controlled by the contacts 79, 80 is 100 closed once to each quarter revolution of the shaft 74. The spring arm 78 permits but a quarter turn of the shaft 74 each time that any one of the arms 73 is engaged by the contact arm 67. Thus it is clear that the circuit controlled by the contacts 67, 68 and also the circuit controlled by the contacts 79, 80 are closed once in each revolution of the shaft 63. It is also clear that contacts 67, 68 engage slightly before the contacts 79, 80, and that there is a slight interval of time between the engagement of the two sets of contacts. 110

A switch is provided for opening and closing the bell ringing circuit and said switch comprises a stationary contact 82 mounted 120 on the housing bottom 7. Adapted to engage 125

the contact 82 is a resilient contact 83 which is fastened at one end to the housing bottom 7 and is provided with an eye 84 pivotally engaged by the lower end of an operating rod 85. The upper end of the rod 85 passes through a hole 86 in the top 87 of the housing and is pivotally connected to one end of a lever 88 which is fulcrumed at 89 on a standard 90 mounted on the top 87. When the free end of the lever 88 is depressed it causes the contact 83 to be raised from the contact 82 so as to open the circuit in which said contacts are included.

On the housing top 87 are mounted a pair of lamp sockets 91 holding incandescent lamps 92, preferably of a ruby or red color.

The various electrical connections may be made as shown diagrammatically in Figure 11, and in said figure I have shown two like signaling mechanisms controlled by one timing mechanism. These electrical connections will now be described: Each bell 42 is connected by wires 93, 94 to one of the coils of the associated transformer 43, and one end of the other coil of each transformer is connected by a wire 95 to the associated switch contact 83. The other switch contacts 82 are connected to wires 96 which are grounded at 97. The transformers 43 are connected by a wire 98 which, in turn, is connected by a wire 99 to the contact arm 68. The contact 67 is connected by a wire 100 to one of the current mains 101. Thus when the switch 82, 83 is closed and the contacts 67, 68 are engaged, the bells 42 will ring.

The other electric current supply main 102 is grounded, as indicated at 103. The motor 45 is connected by a wire 104 to a switch contact 105 adapted to be engaged by a switch contact 106 connected by a wire 107 to the main 101. Thus when the switch 105, 106 is closed, the motor 45 will operate.

The standard 81 is connected by a wire 108 to the wire 100 and the spring arm 78 is connected by a wire 109 and branches 110, 111 to the motors 8. The motors 8 are connected to wires 112, grounded as indicated at 113. Thus when the contacts 79, 80 are closed the motors 8 will be energized.

The lamp sockets 91 of each pair of lamps 92 are connected together by a wire 114 which is grounded as indicated at 115. The lamp sockets 91 are also connected together by wires 116 which are connected by a wire 117, and the wire 117 is connected to a wire 118 that is connected to a switch contact 119. The associated switch contact 120 is connected by a wire 121 to the main 101. When the switch contacts 119, 120, are closed, the lamps 92 are supplied with electric current.

From the foregoing, it is seen that duplicate signaling mechanisms are to be placed at different street intersections and are electrically connected by the three wires 98, 111, 117. It is preferable to place the signaling

mechanisms in the center of the street intersections and, when this is done, I prefer to form a groove in the street surface extending from one signaling mechanism to the other and place the wires 98, 111, 117 in said groove. After the wires are in place the groove will be filled up with asphalt or other suitable electrical insulating material.

The operation of the traffic signal is as follows: Assuming that all of the switches are closed and that the contact arm 67 is in the dotted line position *b* in Figure 8, the motor 45, through the connections hereinbefore described, will turn the arm contact 67 clockwise in Figure 8.

In the course of its motion the arm contact 67 will engage the contact 68, thereby closing the bell circuit and ringing the bells 42. The ringing of the bells is a preliminary warning to the pedestrians and the drivers of vehicles approaching the intersections that the semaphore signals are about to be turned. As the arm contact 67 continues to rotate, it depresses the contact 68 so as to permit the contact 67 to pass by the contact 68. As soon as the contact 67 leaves the contact 68 the bell-ringing circuit will be opened and the bells will discontinue ringing. This is a warning that the traffic should stop. There is preferably an interval of a second or two between the time that the contact 67 leaves the contact 68 and the engagement of the contact 67 with one of the arms 73.

The arm 68 now engages one of the arms 73 and turns said arm, thus causing the contact 69 to engage the contact 80 for a short interval of time, thus closing the circuit in which are included the motors 8. The motors 8 are thus energized and each operates to wind its chain 16. Winding up of the chain, as hereinbefore described, causes turning of the shaft 23 and with it the semaphore 32, thus signaling to pedestrians and the drivers of vehicles in the street alined edgewise with the semaphore that they are to proceed through the intersection, and warning the pedestrians and drivers of vehicles in the cross street to stop.

At the end of a predetermined interval of time, for example one-half minute, the contact 67 will have made a complete revolution and again engage the contact 68 so that the cycle of movements just described will again occur to first ring the bell and then cause the semaphore to be given another quarter turn, thus to indicate a change in the flow of traffic through the intersection.

If the contacts 79, 80 should be closed longer than necessary to cause the shaft 23 to be given a quarter turn, the clutch 12, 13 will slip so that no harm can come to the mechanism, the slippage occurring when the slack in the chain 16 between the arm 19 and the screw 17 is taken up. It will be un-

derstood that, as long as the motor 8 operates, the friction between the clutch members will be sufficient to hold the arm 19 against being retracted by the spring 21 and that, as soon as the contacts 79, 80 separate, the spring 21 retracts the arm 19 and the pawl 26 will slip on the ratchet wheel 25 so that the shaft 23 will remain in the position to which it has been turned, said shaft being 10 so held by the spring 27. As soon as the arm 19 has thus been retracted, the parts are re-set in position to be operated again when the contact 67 again engages the contact 68.

If it be desired to discontinue ringing of 15 the bell at any particular street intersection, the switch 82, 83 will be opened at that particular signaling mechanism by operation of the lever 88 into position to move its pivotal connection with the rod 85 into position vertically above the pivot 89.

If a vehicle should run close enough to the housing 1 to strike one of the projecting ends of the semaphore 32, said semaphore will turn horizontally on the shaft 23 to permit the vehicle to pass and said semaphore will then return to the position it was in before the vehicle struck it, as has been described in detail hereinbefore. When the signals are not to be used, for example, in 25 the evening or late at night, the switch 105, 106 will be opened, and then, if desired, the semaphore 32 may be swung in a vertical path into the position shown in dotted lines c in Figure 1.

30 I claim:

1. In a traffic signal, the combination of a 35 vertical shaft, a semaphore mounted to turn horizontally on said shaft, yielding means for maintaining said semaphore in a given position relatively to the shaft, means to operate the shaft in one direction, and means in conjunction with a portion of the shaft operating means to hold said shaft against rotating in the opposite direction when the semaphore is turned in said opposite direction by a moving object striking it.

2. In a traffic signal, the combination of a 40 semaphore, means including a motor to move the semaphore into different positions, an electrically operated audible signal, an electric contact electrically connected with the audible signal, a second electric contact electrically connected with the motor, a third electric contact electrically connected 45 with the motor, a second motor, a contact arm electrically connected with the audible signal and operative by the second motor to intermittently engage the first electric contact, and means intermittently operated by the contact arm to move the third contact into engagement with the second contact.

3. In a traffic signal, the combination of a 50 vertical shaft, a semaphore mounted on said shaft, an electric motor, means oper-

ative by the motor and including a pawl and ratchet device to turn the shaft in one direction when the motor is energized, means cooperating with a portion of the last means to retract the pawl and ratchet device when 55 the motor is de-energized, and means in conjunction with a portion of the pawl and ratchet device yieldingly holding the shaft in the positions to which it is turned.

4. In a traffic signal, the combination of a 60 vertical shaft, a semaphore mounted on said shaft, an electric motor, a friction clutch driven by said motor, an oscillatory member, a pawl and ratchet connection between the oscillatory member and the shaft, a flexible 65 member adapted to be wound up by rotation of the loose clutch member to turn the oscillatory member in one direction, and a spring connected with the oscillatory member and operative to turn the oscillatory 70 member in the opposite direction when the motor is de-energized.

5. In a traffic signal, the combination of 75 an electric motor, a contact arm operative by the motor, an electric contact in the path 80 of travel of the contact arm, a rotative arm in the path of travel of the contact arm, a pair of electric contacts, a motor connected with the last named electric contacts, a rotatably mounted semaphore operated by the 85 motor, an electrically operated auditory signal mounted adjacent the semaphore and electrically connected with the contact arm and first named electric contact, and means operative by the second arm to move one 90 of the last named contacts into engagement with the other of the last named contacts.

6. In a traffic signal, the combination of 95 an electric motor, a rotative contact arm operatively connected with the motor, an 100 electric contact intermittently engaged by the contact arm as said arm rotates, a second rotative arm intermittently engaged by the first arm at a different time than the electric contact, a pair of electric contacts, 105 a motor connected with the last named electric contacts, a rotatably mounted semaphore operated by the motor, an electrically operated auditory signal mounted adjacent the 110 semaphore and electrically connected with the contact arm and first named electric contact, and means operative by the second arm to move one of the last named contacts into engagement with the other of the last named contacts.

7. In a traffic signal, the combination of a 115 motor, a rotatively mounted cam, an arm projecting from the cam, a spring arm engaged by the cam, an electric contact mounted on the spring arm, a second electric contact adapted to be engaged by the first contact when the cam rotates, a third 120 arm rotatively mounted and operatively connected to the motor, a third electric contact mounted to move at right angles to the 125 130

third arm, a motor connected with the last named electric contacts, a rotatably mounted semaphore operated by the motor, an electrically operated auditory signal mounted adjacent the semaphore and electrically connected with the contact arm and first named electric contact, and means yielding- ly holding the third electric contact in the path of travel of the third arm, the first arm being positioned in a plane coincident with the third arm and engageable thereby. Signed at Los Angeles, California this 19th day of July 1921.

JOHN C. BUTTERFIELD.
